UNITED STATES PATENT OFFICE.

JOHN V. MCADAM, OF HASTINGS-UPON-HUDSON, NEW YORK.

COMBINED HOLDER AND COVER FOR VESSELS.

1,200,207.

Specification of Letters Patent. Patented Oct. 3, 1916.

Application filed January 4, 1915. Serial No. 463.

To all whom it may concern:

Be it known that I, JOHN V. MCADAM, a citizen of the United States, and resident of Hastings-upon-Hudson, in the county 5 of Westchester and State of New York, have invented a new and useful Combined Holder and Cover for Vessels, of which the following is a specification.

The object of my invention is to provide 10 a combined holder and cover for removable vessels, such as bottles, jars, and the like, in which the weight of the vessel, when supported by the holder, automatically causes the cover to close the mouth of the vessel.

15 A further object is to provide a device comprising a system of connected levers for producing the result above set forth.

A practical embodiment of my invention 20 is represented in the accompanying drawings, in which—

Figure 1 represents the device in top plan with a vessel suspended therein, certain of the parts being broken away to more clearly show the parts beneath the same, Fig. 2 is 25 a view in front elevation of the device with the vessel suspended therein, Fig. 3 is a side view of the same, and Fig. 4 is a side view of the device showing the positions which the parts assume when the vessel has been 30 removed from the device.

The device comprises a supporting bracket which may be secured to a wall or other support by means of screws 1, which bracket is provided with an outwardly projecting arm 2 and a downwardly projecting arm 3.

The cover 4 is hinged to the free end of the lever 5, the inner end of which lever is hinged to the outwardly projecting arm 2.

40 The vessel suspending lever 6 is hinged at its inner end to the downwardly projecting arm 3 of the supporting bracket, which lever is provided with branches 7 and 8 arranged to partially embrace the neck of the vessel.

45 A link 9 connects the levers 5 and 6 at different distances from their hinged connections with the supporting bracket, the connection of the link with the lever 5 being closer to the hinged connection of said lever

with the supporting bracket than the link's 50 connection with the lever 6 to its hinged connection with the supporting bracket.

A spring 10 leads from the outwardly projecting arm 2 of the supporting bracket to the suspending lever 6, which spring 55 tends to hold the levers 5 and 6 normally raised.

Because of the different distances that the link 9 is connected to the levers 5 and 6, the free end of the lever 5 and the cover carried 60 thereby, will open up the space between it and the free end of the lever 6 as the two levers are raised and will close the space between the cover 4 and the free end of the lever 6 when the levers are depressed. 65

This interconnection between the levers 5 and 6 will permit an ample space to be provided for the reception and removal of the top of the vessel. When the vessel is inserted into position to be suspended from 70 the lever 6, the weight of the vessel will depress the lever 6 and will draw the cover 4 downwardly into snug engagement over the mouth of the vessel, it being the intention to make the spring 10 of sufficient strength 75 to hold the parts with the cover substantially centered on the mouth of the vessel.

In the embodiment of the invention herein illustrated, I have shown the supporting bracket, the levers 5 and 6, and the link 9 80 as of wire bent into the proper shape for performing the functions hereinabove described and for rendering the holder amply rigid and strong.

The wire which forms the bracket support is bent to form two eyes 11 for receiving the fastening screws 1. 85

It is obvious that the several parts may be varied in construction between wide limits without departing from the spirit and 90 scope of my invention; hence I do not wish to limit myself to the particular construction herein shown, but

What I claim is:—

1. A holder for removable vessels including a cover for closing the mouth of the vessel and means controlled by the weight of the vessel for automatically moving the 95

cover into and out of engagement with the mouth of the vessel.

2. A holder for removable vessels including a cover for closing the mouth of the vessel, means controlled by the weight of the vessel for automatically moving the cover downwardly into position to engage and close the mouth of the vessel and means for automatically lifting the cover as the weight 10 of the vessel is removed.

3. A holder for removable vessels including a cover for the vessel, a system of connected levers controlled by the weight of the vessel for automatically moving the cover 15 into position to close the mouth of the vessel and means for automatically lifting the cover as the weight of the vessel is removed.

4. A holder for removable vessels including a cover for closing the mouth of the vessel, a cover carrying lever, a vessel carrying lever and a link connecting said levers whereby the weight of the vessel will automatically cause the cover to engage and close the mouth of the vessel.

25 5. A holder for removable vessels including a cover for the vessel, a cover carrying lever, a vessel carrying lever, a link connecting said levers whereby the weight of the vessel will automatically cause the cover 30 to close the mouth of the vessel, and means for automatically lifting the cover as the weight of the vessel is removed.

6. A holder for removable vessels including a cover for the vessel, a supporting 35 bracket, a cover carrying lever and a vessel carrying lever, both hinged to said bracket, and a link connecting said levers whereby the depression of the vessel carrying lever due to the weight of the vessel will depress 40 the cover carrying lever to cause the cover to close the mouth of the vessel.

7. A holder for removable vessels including a cover for the vessel, a supporting bracket, a cover carrying lever and a vessel 45 carrying lever, both hinged to said bracket, a link connecting said levers whereby the depression of the vessel carrying levers due to the weight of the vessel will depress the cover carrying lever to cause the cover to 50 close the mouth of the vessel, and means for holding the levers normally raised.

8. A holder for removable vessels including a cover for the vessel, a bracket support having outwardly and downwardly projecting arms, a cover carrying lever hinged to the outwardly projecting arm, a vessel carrying lever hinged to the downwardly projecting arm, and a link connecting said levers whereby the depression of the vessel 55 carrying lever due to the weight of the vessel will automatically depress the cover carrying lever to cause the cover to close the mouth of the vessel.

9. A holder for removable vessels includ-

ing a cover for the vessel, a bracket support 65 having outwardly and downwardly projecting arms, a cover carrying lever hinged to the outwardly projecting arm, a vessel carrying lever hinged to the downwardly projecting arm, a link connecting said levers 70 whereby the depression of the vessel carrying lever due to the weight of the vessel will automatically depress the cover carrying lever to cause the cover to close the mouth of the vessel, and means for holding 75 the said levers normally in their raised position.

10. A holder for removable vessels including a cover for the vessel, a suitable support, a cover carrying lever and a vessel 80 carrying lever, both hinged to said support, and a link connecting said levers at different distances from their hinged connections with the support whereby the space between the free ends of the levers is contracted 85 and enlarged as the levers are depressed and raised.

11. A holder for removable vessels including a cover for the vessel, a suitable support, a cover carrying lever, a vessel carrying lever, both hinged to said support, a link connecting said levers at different distances 90 from their hinged connections with the support whereby the space between the free ends of the levers is contracted and enlarged as 95 the levers are depressed and raised, and means for holding the levers normally in their raised position.

12. A holder for removable vessels including a cover for the vessel, a cover carrying 100 lever and a vessel carrying lever, the cover carrying lever being under the control of the vessel carrying lever whereby the weight of the vessel will automatically cause the cover to close the mouth of the vessel.

105 13. A holder for removable vessels including a cover for the vessel, a cover carrying lever and a vessel carrying lever, the cover carrying lever being under the control of the vessel carrying lever whereby the 110 weight of the vessel will automatically cause the cover to close the mouth of the vessel, and means for automatically lifting the cover as the weight of the vessel is removed.

115 14. A holder for removable vessels including a cover for the vessel, a supporting bracket, a cover carrying lever and a vessel carrying lever, both hinged to the said bracket, the cover carrying lever being under the control of the vessel carrying lever 120 whereby the depression of the vessel carrying lever due to the weight of the vessel will depress the cover carrying lever to cause the cover to close the mouth of the vessel.

125 15. A holder for removable vessels including a cover for the vessel, a supporting bracket, a cover carrying lever and a vessel

carrying lever both hinged to the said bracket, the cover carrying lever being under the control of the vessel carrying lever whereby the depression of the vessel carrying lever due to the weight of the vessel will depress the cover carrying lever to cause the cover to close the mouth of the vessel, and means for holding the levers normally raised.

In testimony, that I claim the foregoing 10 as my invention, I have signed my name in presence of two witnesses, this second day of December, 1914.

JOHN V. McADAM.
